US0D1044069S

(12) **United States Design Patent** (10) **Patent No.:** **US D1,044,069 S**
(45) **Date of Patent:** **** Sep. 24, 2024**

(54) **HEADLAMP**

(71) Applicant: **Optimal Ventures, LLC**, Arlington Heights, IL (US)

(72) Inventors: **Patrick McVey**, Palatine, IL (US); **Avery Bellis**, Chicago, IL (US); **Chad Davis**, Oak Park, IL (US); **Jackson Mayfield**, Chicago, IL (US)

(73) Assignee: **Optimal Ventures LLC**, Arlington Heights, IL (US)

(**) Term: **15 Years**

(21) Appl. No.: **29/792,215**

(22) Filed: **Mar. 11, 2022**

(51) LOC (14) Cl. **26-02**

(52) U.S. Cl.

USPC **D26/39**

(57) **CLAIM**

The ornamental design for the headlamp, as shown and described.

DESCRIPTION

FIG. 1 is a perspective view of a headlamp showing the new design;

FIG. 2 is a front view of the headlamp as shown in FIG. 1; FIG. 3 is a rear view of the headlamp as shown in FIG. 1; FIG. 4 is an enlarged right side view of the headlamp as shown in FIG. 1;

FIG. 5 is an enlarged left side view of the headlamp as shown in FIG. 1;

FIG. 6 is top view of the headlamp as shown in FIG. 1; and, FIG. 7 is a bottom view of the headlamp as shown in FIG. 1.

The broken lines in the drawings depict portions of the headlamp that form no part of the claimed design.

1 Claim, 4 Drawing Sheets
